FIG. 1 is a rear perspective view for a cell phone or PDA compact case showing my new design with the hinged door open;

FIG. 2 is a rear perspective view with the hinged door in the closed position thereof;

FIG. 3 is rear perspective view with the hinged door open view thereof;

FIG. 4 is a perspective exploded view thereof;

FIG. 5 is a rear view thereof;

FIG. 6 is a front view thereof;

FIG. 7 is a right side view thereof;

FIG. 8 is a left side view thereof;

FIG. 9 is a top view thereof; and,

FIG. 10 is a bottom view thereof.

The broken lines in FIGS. 1, 3, and 4 depict environmental subject matter only and form no part of the claimed design.

The cell phone, mirror, ID strap and make up insert shown in FIGS. 1, 3 and 4 are for the convenience of illustration.
